UNITED STATES PATENT OFFICE.

RUSSELL H. PARKER, OF BENTON COUNTY, OREGON.

IGNITION-CIRCUIT SWITCH.

Application filed November 5, 1923. Serial No. 672,922.

To all whom it may concern:

Be it known that I, RUSSELL H. PARKER, a citizen of the United States, residing in the county of Benton and State of Oregon,

5 have invented certain new and useful Improvements in Ignition-Circuit Switches, of which the following is a specification, reference being had to the accompanying drawings.

10 This invention relates to improvements in ignition circuit switches and has for an important object thereof the provision of a combination switch for use in the ignition systems of automobiles.

15 A further object of the invention is to provide a device of this character having means whereby an attempt to operate the switch before the combination has been properly manipulated will result in the ringing of an alarm.

20 A further object of the invention is to provide in a combination of this character an ignition switch construction necessitating complete rotation of the ignition switch 25 through 360° before the ringing of the alarm can be terminated.

25 A still further object of the invention is to provide a device of this character which may be comparatively cheaply produced and 30 which is readily applied to the vehicle.

35 A further object of the invention is to provide in combination with a device of this character a cover plate for the combination dials employed, which cover plate hides 40 from view the setting of the dials but permits operation and prevents removal of the ignition key.

45 These and other objects I attain by the construction shown in the accompanying drawings, wherein for the purpose of illustration is shown a preferred embodiment of my invention and wherein:—

50 Figure 1 is a plan view of a combination switch constructed in accordance with my invention, the casing of the switch being shown in section;

55 Figure 2 is a front elevation of the switch structure, the cover plate being removed;

50 Figure 3 is a section on the line 3—3 of Figure 1;

55 Figure 4 is a section on the line 4—4 of Figure 1;

50 Figure 5 is a section on the line 5—5 of Figure 2;

55 Figure 6 is a section on the line 6—6 of Figure 2;

Figures 7 and 8 are rear elevations of the switching disks *a* and *b* respectively; and

Figure 9 is a rear elevation of the ignition switch plate.

Referring now more particularly to the drawings, the numeral 10 indicates a cover plate and 11 a switch plate which plates are arranged in parallel and in spaced relation to one another. The cover plate 10 is provided with a plurality of spaced openings 12 through which are directed the hub portions 13 of arms 14 operating upon the face of the cover plate. The arms 14 each coat with a series of spaced openings 15 formed 65 in the cover plate with the hub of the arm as a center. The end of the arm 14 is provided with a pin 16 for engagement in these openings, the arm being formed of flexible material so that the pin may be withdrawn 70 from an opening in which it is entered and the arm shifted to an adjusted position, at which time upon release of the arm the pin will enter the opening.

The hub portions 13 have each mounted 80 therein a shaft 17, the inner end of which extends into the bore 18 of a hub 19 formed upon the face of the switch plate 11 next adjacent the front plate 10. These hubs have their forward ends reduced, as indicated 85 at 20, thus providing shoulders 21 against which seat disks 22 having a central opening in which the reduced portion 20 extends. The hub portions 13 are provided with rearwardly projecting pins 23 which engage 90 in openings 24 formed in the disks 22. These openings correspond in number and arrangement to the openings 15 of the plate 10 and the engagement of the pins 23 in the openings determines the position of the arm 22 upon the dial formed by the openings 15 which are preferably each identified by 95 indicia.

The inner ends of the shafts 17 are provided with nuts 25 seated in recesses formed in the rear face of the switch plate and serving as a means for preventing withdrawal of the shafts through the bores 18, thereby preventing any accidental change of the arrangement of the disks 22 with relation to 100 their respective arms 14.

Each disk 22 has formed thereon a flange 26 of conducting material, the flange having a slot cut therein, which slot is filled with insulating material, as indicated at 105 27. Each disk has associated therewith a pair of plungers 28 and 29 carried by the

switch plate, each of these plungers being in the form of a stud 30 mounted in the plate and having a shifting cap 31 imposed thereon, a spring 32 surrounding the stud 30 within the cap and urging the cap outwardly for engagement with its disk. These caps provide brushes for engagement with the flange 26 and are preferably diametrically opposed in their point of engagement. The 10 plungers or brushes 28 are of such size that when aligned with the insulating segment 27 they do not come in contact with the metallic portion of the flange while the plungers 29 are of such size that they 15 bridge the insulating segment 27 when aligned therewith. The plungers 28 are connected in series by a wire 33 one end of which is connected with an alarm 34 mounted upon the rear face of the switch 20 plate 11 and in the present instance disclosed as a bell. The plungers 29 are connected in series by a wire 35.

The disks 22 are divided into two classes, generally indicated by the characters *a* and *b*. Of the first class there is preferably but a single disk while of the latter class as many disks 22 may be provided as is desired. The disk 22 of the class *a* has associated therewith yet a third plunger 36 arranged inwardly of the flange 26 so that it does not come in contact therewith, this plunger being similar in construction to the plungers 28 and 29. Each disk 22 of the class *b* has associated therewith two of such 25 plungers. The disk of the class *a* is provided with a conducting segment 37 which is electrically connected to the metallic flange 26 and which engages against the brush 36 when the disk is in one position. 30 In this same position the insulating segment 27 is aligned with the brush 28. Each of the disks of the class *b* is provided with a conducting segment 38 free from connection with the rim and which in one position of the disk electrically connects the pair of plungers 39 associated with the disk. When the disks *b* are in this position the insulating segments 27 thereof are aligned with the plungers 28 associated therewith. 35 The disk *b* next adjacent the disk *a* has one of the plungers 39 thereof electrically connected to the plunger 36 associated with the disk *a* by a wire 40 and the other plunger 39 thereof connected with one of the 40 plungers 39 of the other disk *b* by a wire 41. The last named disk *b* has its remaining plungers 39 extended through an opening 42 in the switch plate for a purpose presently to appear. 45 The wire 35 has arranged therein an additional plunger or brush 43, this plunger being situated adjacent a hub 44 formed upon the panel and similar to the hubs 19 for the mounting of the disks 22. This hub 50 has a reduced portion 45 entering an open-

ing in a disk 46 similar to but smaller than the disks 22. The conducting flange 47 of this disk is provided with the usual insulating portion 48, which insulating portion is of such size that when aligned with the plunger 43 it breaks contact between this plunger and the conducting portion of the flange. Through the bore of the hub 44 a shaft 48 is directed having upon its forward end an ignition key 49, the hub portion 50 of which is provided with pins for engagement in openings 51 formed in the disk 46. The switch plate 11 bears a further plunger 52 which coacts with the flange 47 of the disk 46 and is preferably 55 diametrically opposed as respects the disk from the plunger 43. This last plunger is electrically connected by a wire 53 with one terminal of a source of current B. While the opposite terminal of this source 60 of current is shown as grounded it will, of course, be realized that the circuit may be completed in any desired manner. The second terminal of the bell or alarm 34 will likewise be grounded. The rear face of the front plate 10 is provided with a spring catch 52 coacting with notches 53 formed in the front face of the ignition disk 46 preventing rotation of this disk in one direction. 65

The operation of the mechanism is as follows: If the disks *a*, *b* and *c* are in the position shown in Figure 2 with the insulating portions thereof aligned with the plunger 28, it will be obvious that no current can pass from the flanges 26 to the plunger 28. With these disks in this position, if the ignition key be turned so that the brush 43 engages a portion of the metallic rim 47 of the ignition plate 46 then current will flow from the source through the flange 47 and plunger 43 to the wire 35. From the wire 35 it will be conducted through the conducting segment 37 to the wire 40, from the wire 40 through a brush 39 and segment 38 to the wire 41, from the wire 41 through the brushes 39 and segment 38 to the wire 42 and this wire may lead directly to the ignition to form a lead wire therefor. All wires leading from the switch plate will be enclosed in armored cable, as indicated at 54, so that the wires may not be attacked to change over the circuit. If any of the disks 22 are so shifted that the insulating segment 37 thereof does not align with its plunger 28 then the circuit to the wire 42 is broken as follows: If the disk *a* be misplaced the circuit is broken between the wires 40 and 35. If the first of the disks *b* is misplaced the circuit is broken between the wires 40 and 41 and if the second disk *b* is broken it is broken between the wires 40 and 42 for the reason that the conductor segments 37 or 38, as the case may be, will 110 not properly align with their associated 115 wires. 120

brushes 36 or 39. Furthermore, if any of these disks is misplaced and the ignition key is turned to the "on" position, current will flow from the wire 35 through the flange 26 of the disk to the wire 33 with the result that the alarm is actuated. Since the key 49 can only be rotated in one direction it will be obvious that a complete revolution thereof must be made before the alarm can be 10 silenced.

Apparatus of this character is preferably housed in a casing 55 having pressed lugs 55^a against which the switch plate 11 is seated. The casing is arranged behind the 15 instrument panel 56 of the vehicle to which it is applied, an opening 57 being formed in the panel so that the dials appear therethrough. To the panel a cover plate 58 is preferably hinged which normally covers 20 the operating arms 14 controlling the disks 22, this cover plate having an opening 59 through which the ignition switch is accessible for operation. It will be obvious that the use of a switch constructed in accordance 25 with the foregoing will be extremely difficult for persons not familiar with the combination to so place the ignition switch that the vehicle may be started without attracting attention by the alarm 34. It will 30 furthermore be obvious that this construction is capable of a considerable range of change and modification without in any manner departing from the spirit of my invention and I accordingly do not limit myself 35 to such specific structure as hereinbefore set forth except as hereinafter claimed.

I claim:—

1. A switch including an insulating base, a pair of series of spaced electrically connected contacts carried by the base, a third series of contacts carried by the base, alternate contacts of the third series being electrically connected with one another, the third series of contacts and one of the 40 first named series of contacts each having a contact thereof adapted for connection with a translating device and a plurality of rotatable insulating disks associated with the base, said disks having means whereby any of said disks in all but one position thereof completes a connection between said pair of series of electrically connected contacts, certain of said disks further including a part which in such position of the 45 disks electrically connects unconnected pairs of contacts of the last named series of contacts, a further disk including a part which in the last named position of the disk electrically connects the other of said pair of 50 series of electrically connected contacts with one of the third series of contacts.

2. A switch including an insulating base, a pair of series of spaced electrically con-

nected contacts carried by the base, a third series of contacts carried by the base, alternate contacts of the third series being electrically connected with one another, the third series of contacts and one of the first named series of contacts each having a contact thereof adapted for connection with a translating device and a plurality of rotatable insulating disks associated with the base, said disks having means whereby any of said disks in all but one position thereof completes a connection between said pair of 65 series of electrically connected contacts, certain of said disks further including a part which in such position of the disks electrically connects unconnected pairs of contacts of the last named series of contacts, a further disk including a part which in the last named position of the disk electrically connects the other of said pair of 70 series of electrically connected contacts with one of the third series of contacts, an operating handle for each disk and means for determining the position of the operating handle in which the disk is arranged in the last named position.

3. A switch including an insulating base, 90 a pair of series of spaced electrically connected contacts carried by the base, a third series of contacts carried by the base, alternate contacts of the third series being electrically connected with one another, the 95 third series of contacts and one of the first named series of contacts each having a contact thereof adapted for connection with a translating device and a plurality of rotatable insulating disks associated with the 100 base, said disks each including an arcuate contact having a notch, an insulating material within the notch, each disk aligning with one contact of each of the pairs of series of electrically connected contacts, the 105 contacts of one of the series of electrically connected contacts being of a width less than the insulating portion of the arcuate contacts of the disks, the contacts of the other of the series of electrically connected 110 contacts being of greater width than such insulating portion whereby said disks in all but one position thereof will electrically connect the pair of series of electrically connected contacts, one of the arcuate contacts of one of said disks having an extension which in such position of said disk aligns with and engages a contact of the third series of contacts, the remaining disks each having a further segment which in said 115 position aligns with and provides a connection between a pair of unconnected contacts of the third series.

In testimony whereof I hereunto affix my signature.

RUSSELL H. PARKER.
